UNITED STATES PATENT OFFICE.

GEORGE FRANCOIS JAUBERT, OF PARIS, FRANCE.

RESPIRATOR.

No. 914,576.

Specification of Letters Patent. Patented March 9, 1909.

Application filed December 20, 1907. Serial No. 407,376.

To all whom it may concern:

Be it known that I, GEORGE FRANCOIS JAUBERT, a citizen of the Republic of Switzerland, residing at 155 Boulevard Malesherbes, Paris, France, have invented certain new and useful Improved Respirators, of which the following is a specification.

This invention has for its object improvements in respiratory appliances enabling atmospheres of deleterious or unbreatheable gases to be entered and remained in and which comprise reservoirs of air or gas or of respirable gaseous mixtures under pressure.

The invention relates more particularly to the gas supply device, that is to say the arrangement and the means for insuring respiration in the event of certain parts becoming obstructed.

In the accompanying drawing:—Figure 1 is a general view of a constructional form of the apparatus. Fig. 2 is a detail view of the modified form of apparatus.

The apparatus comprises a battery of say four reservoirs *a b c d* of steel or other appropriate material containing air, gas or other respirable gaseous mixtures under pressure. These reservoirs are mounted on a tube *z* upon which a gas supply valve or cock *e* is arranged. The reservoirs *a b c* are in direct communication with this cock; the reservoir *d* or emergency reservoir communicates with the tube *z* by the intermediary of a separate valve or cock *f* provided with an operating rod *g*.

The gas supply valve *e* is connected by means of a pipe *x* with a pressure reducing valve *h* controlled by a handle *i* and terminating in the discharge pipe *m*. The passage *x* is also provided with a pressure gage *j* and a branch valve *k* enabling direct communication to be established with the pipe *m* through the small branch *x'*. The pipe *m*, which is preferably flexible, opens into a regulating bag or pocket *o* of material impermeable to gas and which may be flexible or rigid; from this pocket there proceeds the aspiratory pipe *p* ending in a nozzle *y* on which there is fixed a mouthpiece *n* preferably composed of a material such as india-rubber. From the nozzle *y* there is branched an expiratory pipe *r* provided with a valve *s* opening outward. The aspiratory pipe *p* likewise contains a valve *q* opening into the nozzle *y*.

The operation is as follows: In the first place the reservoirs are charged with air, gas

or respirable gaseous mixture under pressure. At a pressure of say 150 atmospheres about 900 liters of gas can be stored in a reservoir having a capacity of 1.5 liters. The apparatus is then fitted to the body of the person who is to use it, the reservoir being attached to the chest or to the back by means of belts passing through the loops 1, 2, 3, and 4. The india-rubber part *n* at the end of the nozzle *y* is placed in the mouth. At the beginning the cocks *e* and *f* being closed the cock *e* is first of all opened, then the handle *i* of the pressure reducing valve is depressed to enable the gas to flow through the pipe *m* into the pocket *o*, then through the aspiratory pipe toward the pipe *y* and the mouthpiece *n*, which is only placed in the mouth after an adequate provision of gas has collected in the pocket *o*. The supply through the reducing valve *h* may be regulated in the following manner:—When the workman has only to perform a moderate amount of work, he arranges the handle *i* of the reducing valve in such a manner that the valve permits of a supply of 10 liters of air per minute; when, however, the work is hard, he arranges the handle so as to obtain a supply of 20 liters. The aspiration of the air takes place through the pipe *p* and the valve *q* preventing the entrance of unbreatheable gases; during expiration, on the other hand, the valve *q* is closed and the valve *s* opens to permit of the escape of the respiration gases. The pressure gage *j* shows the quantity of respirable gas remaining in the cylinders at any moment. When the cylinders *a b c* are empty, the cock *f* is opened for the consumption of the reserve of gas in the cylinder or cartridge *d*. The workman should now retire from the place containing the unbreatheable atmosphere, the provision of air remaining in the cylinder *d* giving him ample time to do so. It may happen that owing to rust forming in the steel cylinders the fine perforations of the reducing valve will become choked. The valve *k* is then opened and the respirable gases are able to flow directly into the pipe *m*; in this case the flow of respirable gases taking place without any reduction of the pressure, it is advisable not to open the branch valve *k* completely, and to withdraw at once from the foul atmosphere. The apparatus therefore presents every guarantee of safety; the workman is warned that he must withdraw as soon as he perceives that the first three cylinders *a b c* are exhausted and the fourth cyl-

inder *d* supplies him with all the air necessary during such withdrawal.

The duration of respiration permitted by the four cylinders of this apparatus is from 5 90 to 45 minutes, according as the supply furnished is 10 to 20 liters. The duration of the utilization of the apparatus may of course be increased or diminished by altering the number of cylinders, their dimensions and 10 the pressure of the gas.

Fig. 2 represents a constructional form of apparatus with a single reservoir. The reducing valve *h* is regulated by means of a screw *t* with stop yoke *u*. The branch valve 15 *k* is connected by means of a flexible pipe *w* with the nozzle *v* to which the discharge pipe is fitted.

The operation of the apparatus is the same; the pressure gage *j* furnishes a check on the 20 quantity of air contained in the cylinder *a* and the branch valve *k* enables the air to reach the mouthpiece directly if the perforations in the reducing valve *h* should become obstructed by rust.

25 The apparatus is intended for work in mines, at fires, and generally speaking, in all places where the air contains an atmosphere of unbreathable gas.

Having now particularly described and ascertained the nature of my said invention and in what manner the same is to be performed, I declare that what I claim is:

1. In a respiratory appliance of the character described, a reservoir for containing a 30 respirable gas under pressure, a supply pipe 35

leading from said reservoir, an aspiratory pipe, a pressure reducing valve between the supply pipe and the aspiratory pipe, a by-pass around the pressure-reducing valve, and manually operable control valve in the by-pass, substantially as described. 40

2. In a respiratory appliance of the character described, a battery of reservoirs for containing a respirable gas under pressure, a supply pipe common to said reservoirs, an 45 aspiratory pipe, a pressure reducing valve between the supply pipe and the aspiratory pipe, and a manually operable auxiliary valve between one of the reservoirs and the supply pipe, substantially as described. 50

3. In a respiratory appliance of the character described, a battery of reservoirs for containing a respirable gas under pressure, a supply pipe common to said reservoirs, an aspiratory pipe, an adjustable pressure reducing valve between the supply pipe and the aspiratory pipe, a by-pass about the pressure reducing valve, a manually operable control valve in the by-pass, and a manually operable auxiliary valve between one of the reservoirs and the supply pipe, substantially as described. 55

In witness whereof I have hereunto set my hand this twenty first day of November, 1907.

GEORGE FRANCOIS JAUBERT.

In the presence of two witnesses:

MILTON B. KIRK,

HENRY SCHWAB.
